SAFETY RAZOR

Martin Glaberson, Stratford, and George L. Schick, Trumbull, Conn., assignors to Warner-Lambert Company, Morris Plains, N.J.

Filed Oct. 3, 1972, Ser. No. 294,751

Term of patent 14 years

Int. Cl. D28—03

U.S. Cl. D95—3 A

FIG. 1 is a rear elevational view of a safety razor, showing our new design;

FIG. 2 is a side elevational view thereof;

FIG. 3 is a front elevational view thereof;

FIG. 4 is a top plan view thereof; and

FIG. 5 is a bottom plan view thereof.

The side view not shown is substantially a mirror image of FIG. 2.

We claim:

The ornamental design for a safety razor, as shown and described.
